(57) **CLAIM**

The ornamental design for an alcohol sleeve with display window as shown and described.

DESCRIPTION

FIG. 1 is a front perspective view of the alcohol sleeve with display window.

FIG. 2 is the front view of the alcohol sleeve with display window.

FIG. 3 is a back view of the alcohol sleeve with display window.

FIG. 4 is a side view of the alcohol sleeve with display window.

FIG. 5 is the other side view of the alcohol sleeve with display window.

FIG. 6 is top view of the alcohol sleeve with display window.

FIG. 7 is a bottom view of the alcohol sleeve with display window.

FIG. 8 is a perspective view of the alcohol sleeve with display window in an environment of use.

FIG. 9 is a perspective view of the alcohol sleeve with display window in an alternative environment of use; and, FIG. 10 is a perspective view of the alcohol sleeve with display window in an additional alternative environment of use.

In the drawings, the broken lines show portions of an alcohol sleeve with display window that form no part of the claim.

1 Claim, 5 Drawing Sheets
